UNITED STATES PATENT OFFICE.

ARTHUR E. PICKLE, OF NEVADA, MISSOURI.

IMPROVEMENT IN COMBINATION-LOCKS.

Specification forming part of Letters Patent No. 146,201, dated January 6, 1874; application filed November 8, 1873.

To all whom it may concern:

Be it known that I, ARTHUR E. PICKLE, of Nevada, in the county of Vernon and State of Missouri, have invented a new and Improved Permutation-Lock, of which the following is a specification:

In the accompanying drawings, Figure 1 represents a front elevation of my improved permutation-lock with parts cut off to show construction beneath, and Fig. 2 is a vertical transverse section of the same on the line *c c*, Fig. 1.

Similar letters of reference indicate corresponding parts.

The object of my invention is to furnish a neat and convenient permutation-lock for post-office boxes, trunks, safes, and other similar purposes, which recommends itself by its simplicity and cheapness for a variety of applications for which the more complex constructions of permutation-locks are less advantageous on account of their size and expense.

My invention consists of a rotating plate, having a projecting pin at one end, which engages the locking-bolt, so as to withdraw the same in part by means of the inner pin of a rotating dial-plate acting upon a projecting band-spring, attached to the rotating plate. The withdrawal of the lock-bolt is completed by the action of a second pin of the dial-plate on the bolt, which is recessed and provided with inclined front and rear projections for the same. The pins of the dial-plate may be changed to any combination of letters by being placed into any two holes of the concentric series of perforations provided therein.

In the drawing, A represents the back rotating plate, which is of disk or other shape, and turns freely on the central bolt *a*. At diametrically opposite points of plate A are arranged the fixed pin *b* and the outward-projecting band-spring *d*. Pin *b* is placed at or near the outer periphery of plate A, so as to engage the slightly projecting top part of bolt B and raise the same from its seat. Bolt B slides in a recess of the door or frame to which the lock is applied, and is formed in such a shape that the top part is of T-shaped cross-section, as indicated in Fig. 2, with raised

projections *b'*, said projections having inclined sides against which the pins *b* and *g'* act in withdrawing the bolt. The dial-plate C rotates also freely on central bolt *a*, or on a disk-shaped head of the same, and is turned by a knob or button, *e*. An outer and inner concentric series of perforations, *f*, of the dial-plate C, correspond in number and position with the letters or figures stamped thereon. Two pins, *g* and *g'*, are placed into dial-plate C, one, *g*, in the inner, and the other, *g'*, in the outer series of perforations *f*, under any desired combination of the letters, which may be formed thereby. The pins *g* and *g'* project from the rear side of dial-plate C, the inner pin *g* serving to engage the band-spring *d*, when carried against the edge of the same, but passing easily over the spring from the opposite direction. When, therefore, the dial-plate is turned so as to engage, by inner pin *g*, spring *d* of rotating plate A, and to carry the same along till the corresponding letter is placed diametrically opposite to bolt B against a suitable index or a recess, *h*, of top or incasing plate D, the pin *b* raises the bolt B as far as permitted by the inclined rear projection *b'*. By turning then the dial-plate in opposite direction till the second letter is brought into recess *h*, diametrically opposite to outer pin *g'*, bolt B is thereby engaged at its front projection *b'* and entirely raised from its seat, so that the door may be thrown open. It is evident that the outer perforations of the dial-plate have to be arranged at such distance from the circumference that the outer pin *g'* withdraws, by means of the inclined front projection *b'*, the bolt entirely from its contact with the socket or seat. By straightening or recessing slightly the lowermost point of bolt projections *b'* the pins catch more effectively therein and secure more fully the exact movements of the bolt. The bolt is thrown down or outward into its groove by its own gravity as soon as the rotating dial-plate is turned, on closing the pivoted door to which the lock is applied into a vertical position.

Having thus described my invention, I claim as new and desire to secure by Letters Patent—

1. The permutation-lock, consisting of dial-plate C, provided with changeable setting-pins

g and *g'*, in combination with rotating plate A and bolt B, arranged and operated as and for the purpose described.

2. The dial-plate C, arranged with two concentric series of perforations, *f*, corresponding to the letters of the same for the changeable combination of the setting-pins *g* and *g'*, as set forth.

3. The rotating plate A, having an outer pin,

b, and outward-projecting band-spring *d*, as described.

4. The sliding bolt B, having top part with T-shaped cross-section, and inclined face and rear projections *b'*, substantially as and for the purpose set forth.
